AERATION APPARATUS

James Lockey, Great Burgh, Epsom, England, assignor to Standard Brands Incorporated, New York, N. Y., a corporation of Delaware

Application July 24, 1936, Serial No. 92,354
In Great Britain August 23, 1935

6 Claims. (Cl. 261—93)

This invention relates to an apparatus for contacting gaseous and liquid materials, especially for the aeration of liquids or dispersion of gases or vapors in liquids, and more particularly to fermenters used in the manufacture of yeast on the aeration principle.

A general object of the invention is to provide an apparatus whereby gases and liquids may be contacted, which is economical of manufacture, simple yet durable and sturdy of construction, and easy to clean and to operate.

Specific objects of the invention are to provide an apparatus which is capable of dispersing large volumes of air or other gasiform fluid in a liquid, create vigorous turbulence without requiring a large expenditure of power and which provides an aeration chamber which preferably is so shaped that notwithstanding the differences of hydrostatic pressure due to different depths of submergence of different zones of the chamber the air or gas is ejected efficiently and uniformly at the different zones.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had to the following detailed description taken in connection with the accompanying drawing, in which Fig. 1 is a sectional elevational view illustrating a preferred form of the invention.

Generally, the present invention comprises an aerating apparatus having a perforated or equivalent multiple gapped chamber rotatable in a submerged position within a suitable receptacle, as a fermenting vat or similar reaction vessel. A passage or group of passages leading to the space above the submerging liquid is provided so that when the chamber is rotated and the liquid therein is ejected through the perforations or gaps by centrifugal force the air or gas above the liquid will be induced to flow down the passage or passages and be similarly ejected. In order to insure that the liquid surrounding the submerged chamber shall not rotate quietly with it, and to prevent formation of a vertical cavity around said chamber, any suitable independent agitating means may be provided, or the vat or other liquid container may be shaped to hinder smooth circular motion of the liquid.

Referring more particularly to Fig. 1 of the drawing, there is shown a submerged chamber 10 which consists of an upwardly tapering cone of perforated metal having a perforated cylindrical neck 11 reaching up beyond the surface of a liquid mass 12 in a vat 13 containing the liquid to be aerated. A vertical stem or central spindle 14 carrying a gear wheel or pulley 15 enables the chamber with protruding neck to be rotated at any desired speed. As the liquid is initially flung out through the perforations 16 it becomes replaced by air which in turn is whirled and flung out and projected into the external surrounding liquid mass. Even if the perforations are relatively coarse as is preferably for cleaning purposes, the air streams become finely dispersed in the surrounding liquid owing to the nature of the discharge and moreover the liquid is violently agitated, especially if the rotation of the mass is impeded as, for example, by a series of baffles 18 vertically supported by an upper and lower framework 17, 17, fitting against the internal wall of the reaction vessel. The spindle 14 carrying the rotatable chamber 10 is journaled in this framework as at 19 and 20.

Owing to the shape of the chamber a film-like pad of issuing air is formed on the outside of the submerged portion. Thereby friction with the surrounding liquid is substantially eliminated and the power required to rotate the chamber is correspondingly reduced.

As it is desirable, for some purposes, to purify the air entering the submerged chamber or to supply some particular gas thereto, the top of the chamber may be closed and the air or gas be supplied through a pipe.

It will thus be seen that the objects hereinbefore set forth are efficiently and economically attained and since certain changes may be made in the above construction and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent, is:

1. An apparatus for contacting a gasiform fluid with a liquid comprising in combination a reaction vessel containing a reaction mass, baffles to aid in agitating said mass and a partially submerged rotatable chamber having a film-forming upwardly converging frusto-conical portion positioned in said vessel adapted to admit a gasiform fluid.

in its unsubmerged portion and to expel said gasiform fluid throughout its submerged portion to form a film-like pad of the gasiform fluid on the outside surface of said frusto-conical portion substantially to eliminate friction of said mass with said chamber and uniformly to disperse said fluid throughout said reaction mass.

2. In an apparatus for contacting a gasiform fluid with a liquid, a rotatable chamber having a cylindrical portion adapted to admit a gasiform fluid and an upwardly converging frusto-conical portion adapted when submerged in a liquid uniformly to expel said fluid therein and to form a film-like pad of the gasiform fluid between said frusto-conical portion and said liquid.

3. An apparatus for contacting a gasiform fluid with a liquid comprising in combination a vessel containing a liquid, a partially submerged rotatable body having an unsubmerged gasiform fluid admission passage positioned therein and an upwardly converging frusto-conical portion upon the outer surfaces of which portion a film-like pad of gasiform fluid forms, the walls of said body being perforated substantially throughout their entire area and agitating means between said body and said vessel.

4. An apparatus for contacting a gasiform fluid with a liquid comprising in combination a reaction vessel containing a reaction mass, a rotatable chamber having an unsubmerged gasiform fluid admission passage positioned therein and an upwardly converging frusto-conical portion upon the outer surfaces of which portion a film-like pad of gasiform fluid forms, the walls of said chamber being perforated substantially throughout

their entire area and means affixed to said vessel to hinder smooth circular action of said mass, said chamber being adapted when partially submerged to expel gasiform fluid through the walls of its submerged portion.

5. An apparatus for contacting a gasiform fluid with a liquid comprising in combination a reaction vessel containing a reaction mass, a rotatable chamber having an unsubmerged gasiform fluid admission passage positioned therein and having an upwardly converging frusto-conical portion upon the outer surfaces of which portion a film-like pad of gasiform fluid forms, the walls of said chamber being perforated substantially throughout their entire area and baffles to agitate said mass, said chamber being so shaped that when partially submerged it is adapted to expel gasiform fluid evenly and uniformly throughout different zones of said mass to accommodate differences in hydrostatic pressure.

6. An apparatus for contacting a gasiform fluid with a liquid comprising in combination a reaction vessel containing a reaction mass, an upper and lower framework carrying spaced apart baffles, and a perforated chamber having an unsubmerged gasiform fluid admission passage and an upwardly converging frusto-conical portion upon the outer surfaces of which portion a film-like pad of gasiform fluid forms partially submerged in and adapted to expel fluid uniformly throughout said mass, the walls of said chamber being perforated substantially throughout their entire area.

JAMES LOCKEY.
